UNITED STATES PATENT OFFICE.

PAUL F. YUNGLING, OF LOS ANGELES, CALIFORNIA.

PACKING GLAND.

Application filed July 19, 1924. Serial No. 727,091.

This invention relates more particularly to a means for adjusting the expansible members of packing glands.

In the drawings annexed hereto the invention is illustrated in connection with a hydraulic rotary swivel head employed to direct a stream of mud-laden water to the cutting bits in the drilling of oil wells by the rotary method. Owing to the gritty character of the mud-laden water passing through the head, the glands require frequent readjustment of the packing elements, this operation in heads now generally employed necessitating a stoppage of drilling operations and a dismantling of the mechanism in order to effect an adjustment. By means of the present invention an adjustment of the expansible packing rings of a gland may be quickly and easily effected from the exterior of the apparatus without the necessity of stopping its operation or dismantling a portion of its casing.

A main object of this invention is to provide a packing gland for encased structures in which the expansible members may be readily adjusted without the necessity of dismantling or removing any portion of the structure.

Another object is to provide a hydraulic swivel head construction having means connected thereto and operated by the rotary liquid feed pipe for diverting foreign matter away from the adjustable packing glands during its operation, whereby to prevent an abrasive or cutting action on the expansible members of the glands.

With the above related objects in view, the invention consists of the parts, improvements, and combinations hereinafter set forth and particularly pointed out in the appended claim.

In the drawings forming a part of this specification, and wherein the same reference numerals are used to designate like parts throughout:

Fig. 1 is a side elevation of a rotary swivel head embodying the features of the invention.

Fig. 2 is an enlarged partial side elevation of the swivel head, parts being shown in section to clearly disclose the invention.

Fig. 3 is a transverse section of the head taken on line 3—3 of Fig. 2.

Fig. 4 is a detail section of one of the packing gland adjusting means.

Fig. 5 is a plan view of the impeller uti-

lized to direct foreign matter away from the packing glands during the drilling operation.

Fig. 6 is a cross section of the impeller taken on line 6—6 of Fig. 5.

Referring to the drawings, 10 indicates a rotary hydraulic swivel head used in the drilling of oil wells, consisting of a casing 11 for the mechanisms, the usual bail 12 for suspending the apparatus being pivotally attached to the casing. The upper portion of the casing includes a gland housing 13 provided on its upper end with a water bonnet 14 through which the mud-laden water passes to the head, the bonnet being bolted or otherwise secured to said housing. The upper end of the gland housing is provided with a cylindrical bore 15, its upper end being threaded for the reception of a gland nut 16 bevelled inwardly on its lower end, a plurality of packing rings 17, formed of an expansible material being disposed in the bore 15 below the gland nut, and surrounding the wash pipe 18. Loosely mounted on this pipe is a circular gland adjusting collar 19 bevelled inwardly on its upper circular end and engaging the lowermost packing rings. Formed integrally with the lower circular end of the gland adjusting collar 19 are a pair of downwardly extending inclined oppositely disposed lugs 20, each provided on their ends with a slot 21. Gland housing 13 is provided in the inclined portion of its circular wall with a pair of oppositely disposed opening 22, through which are passed T-bolts 23, the cross bars of the bolts engaging the slots formed in the lugs 20, adjusting nuts 24 having washers 25, being secured to the bolts.

As the packing rings become cut and worn, the gland adjusting collar 19 may be quickly forced upwardly against the packing rings by means of the T-bolts without necessitating the stoppage of the well drilling operations, and without dismantling any portion of the apparatus, the collar being forced evenly and firmly against the lowermost ring of the packing members. Should the rings become so badly worn as to require replacement, or the addition of another ring, the water bonnet may be removed together with the gland nut, the adjusting collar 19 is then lowered and a new ring inserted in the upper end of the gland. The lower transverse wall 26 of the gland

housing is provided with a packing gland 27, of usual construction, through which passes the lower end of the wash pipe. The wall of the gland housing is provided with a pair of oppositely disposed openings 28 that extend upwardly from wall 26 and terminate adjacent the lower end of the bore 15.

Disposed in chamber 29 of the gland housing, and rigidly secured to the lower end of the wash pipe 18, is an impeller 30, here shown as formed of two semi-circular sections 31, 32, secured together by means of clamping bolts 33. As the mud-laden water 10 passes downwardly through the wash pipe 18, any leakage of the same through the gland will be forced outwardly from the chamber 29, through the openings 28 in the housing wall, thereby maintaining the chamber 29 comparatively free of gritty foreign matter that tends to cut the packings of the glands. In Fig. 2 of the drawings it will 15 be observed that the upper surface of the transverse wall 26 inclines from the center 20 outwardly, the inclination serving to prevent accumulations adjacent the lower gland 25 27 during the operation of the apparatus.

From the above description it will be noted that I have provided a gland construction that is extremely efficient, and one 30 that can be readily adjusted with simple

tools, and further, I have provided means for effectively deflecting accumulations of foreign matter away from the glands during the operation of the apparatus. 35

What I claim is:

In a hydraulic swivel, the combination with a trunnion block and a bail supporting the same, of a hollow shaft extending through said block, a housing secured to the upper end of said block, said housing having aligned shaft bearings in its upper and lower ends, an expandable packing for the lower bearing, a hollow gland nut for the upper bearing, a packing expanding collar 40 mounted in the lower end of said bearing having lugs projecting from its lower end, an expandable packing interposed between the oppositely disposed ends of the gland nut and expanding collar, a threaded bolt 45 pivotally secured to each of said expanding collar lugs, said bolts passing through the housing, and adjusting nuts secured to said bolts and bearing against the outer surface of said housing, whereby the expanding collar 50 may be adjusted to expand the packing of the bearing.

In witness that I claim the foregoing I have hereunto subscribed my name this 21st day of June, 1924.

PAUL F. YUNGLING.
